[57] **CLAIM**

The ornamental design for a housing for electrical and mechanical components, as shown.

DESCRIPTION

FIG. 1 is a perspective view of a housing for electrical and mechanical components, according to one preferred embodiment of this invention;

FIG. 2 is a front view of the housing for electrical and mechanical components, as shown in FIG. 1;

FIG. 3 is a side view of the housing for electrical and mechanical components, as shown in FIG. 1;

FIG. 4 is a side view of the housing for electrical and mechanical components, opposite the side view as shown in FIG. 3;

FIG. 5 is a rear view of the housing for electrical and mechanical components, as shown in FIG. 1;

FIG. 6 is a top view of the housing for electrical and mechanical components, as shown in FIG. 1; and,

FIG. 7 is a bottom view of the housing for electrical and mechanical components, as shown in FIG. 1.
